US0D1045383S

(12) **United States Design Patent** (10) **Patent No.:** **US D1,045,383 S**
(45) **Date of Patent:** **** Oct. 8, 2024**

(54) **BACKPACK**

(71) Applicant: **Guangzhou Xingyue Trading Co., Ltd.**, Guangzhou (CN)

(72) Inventor: **Heng Luo**, Gaozhou (CN)

(73) Assignee: **Guangzhou Xingyue Trading Co., Ltd.**, Guangzhou (CN)

(*) Notice: Patent file contains an affidavit/declaration under 37 CFR 1.130(b).

(**) Term: **15 Years**

(21) Appl. No.: **29/935,210**

(22) Filed: **Mar. 29, 2024**

(51) LOC (14) Cl. **03-01**

(52) U.S. Cl.

USPC **D3/217; D3/283**

(58) **Field of Classification Search**

USPC D3/216–217, 233, 273, 283, 289–290

CPC A45F 3/04; A45F 3/08; A45F 3/047; A45F 4/02; A45F 2003/045; A45C 13/02; A45C 3/00

(57) **CLAIM**

The ornamental design for a backpack, as shown and described.

DESCRIPTION

FIG. 1 is a front perspective view of a backpack, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the backpack shown in an alternate handheld mode; and,

FIG. 10 is a rear perspective view of the backpack shown in the alternate handheld mode of FIG. 9.

The broken lines in the drawings illustrate the portions of the backpack, which form no part of the claimed design.

1 Claim, 10 Drawing Sheets
